UNITED STATES PATENT OFFICE.

JAMES E. COSSAIRT, OF PLATTE CENTER, NEBRASKA.

CAR-DOOR CLAMP.

Application filed June 24, 1922. Serial No. 570,602.

To all whom it may concern:

Be it known that I, JAMES E. COSSAIRT, a citizen of the United States, residing at 5 Platte Center, in the county of Platte and State of Nebraska, have invented certain new and useful Improvements in Car-Door Clamps, of which the following is a specification.

The present invention relates to improvements in the manner of securing the doors 10 of railway cars and more particularly to clamps for doors used on grain carrying cars.

The main object of the invention is to 15 make the doors tight in order to prevent grain leakage, about seventy-five per cent of such cars having this defect.

Another object of the invention is to substitute the tight fitting clamps forming the 20 subject matter of this invention, for the prevalent method of securing the doors by nails or the like, which destroys more grain cars than anything else. By using these clamps the life of the doors as well as the cars is 25 considerably prolonged, as the doors may be positioned and removed rapidly without the slightest injury.

One advantage of the use of these clamps is that it requires much less work and will 30 take considerably less time to install or remove the doors, with a consequent saving in labor and expense.

Another advantage in using this construction is that the doors are held firmly and 35 will not rattle and there is no chance for them to work endwise.

The preferred construction of the device is illustrated in the accompanying drawings, in which:

40 Figure 1 is a perspective view of a grain car seen from the outside and with the clamp device installed,

Figure 2 is a sectional view along line 2—2 of Figure 1,

45 Figure 3 is a longitudinal sectional view of the car,

Figure 4 is a perpendicular sectional view along line 4—4 of Figure 1, and

50 Figure 5 is a horizontal sectional view along line 5—5 of Figure 3.

In the drawings, the reference numeral 10 represents a grain car having a pair of wooden door posts 11, between which is formed the door opening 12. The door posts 55 are secured, in the usual manner, between the boards forming the side wall 13 of the car,

Along each post 11 is placed a structural section preferably of L-shaped iron 14 having a long leg 15 attached to the post and an inwardly projecting short leg 16. Parallel 60 with the short leg 16 is secured a jamb 17 preferably made of angle iron, and forming a perpendicular channel between the jamb and the short leg. Between the two jamb 17, the grain door 18 fits loosely so as to be 65 easily installed in position.

The short leg 16 carries two or more hinges 19 attached thereto by means of screws or rivets and the swinging leaves 20 of the hinges carry a flap 21 adapted to extend across the channel formed between the jamb and the short leg and engage with the side edge 22 of the door. It will be noted 70 that the thickness of the door is greater than the width of the jamb so that the latter does 75 not interfere with the tightening of the flap 21 against the door edge 22.

A clamping bolt 23 turns freely in suitable apertures 24 and 25 provided in the long leg 15 and the flap 21 respectively. Each of 80 these bolts 23 is formed with a solid head 26 at one end and has a rigidly attached nut 27 at its other end, and has threaded connection with the jamb 17, as at 28. In the wall and door post 11 is formed a recess 29 for each of the bolts on the outside of the car, so that the clamping bolts are at no time exposed 85 beyond the outer surface of the wall, but are easily engaged by means of a socket wrench 30 which is carried in a pocket 31 provided 90 in the outside of the car wall preferably to the left of the door. It will now be evident that the tightening of the flap 21 against the door 18 to press it firmly against the long 95 leg 15 of the L-shaped iron 14, can be accomplished by turning the clamping bolts 23 by means of the socket wrench, either from the outside or from the inside of the car, as most convenient at the time. For instance, in preparing the car for loading, the door would 100 be installed between the jamb 17 while the flaps 21 are open and the clamping bolts 23 are screwed inwardly as far as they will go. The flaps 21 are then turned inwardly 105 against the door on their hinges 20 and the clamping bolts 23 tightened from the inside of the car. On the other hand, when unloading the car, it would be more convenient to loosen the bolts from the outside by applying the socket wrench to the heads 26 of the 110 clamping bolts.

As the level of the grain, as a rule, only

reaches about midway up in the car, as indicated at 32, the flaps 21, the jambs 17, and structural L-shaped iron 14, do not need to reach up to the top of the car and may terminate, as seen in Figure 3, some distance therefrom, but there is no reason why they cannot extend all the way or any distance up in the car that may be found most advantageous for different purposes. Usually, 10 the height of door 18 is, however, about three-fourths of that of the opening.

It is also evident that the use of the device is not limited to grain cars alone but may be applied to cars for carrying lime, 15 salt, or any other perishable material.

As no nails are required to secure the doors, the latter may be used indefinitely and the life of the doors as well as the cars will accordingly be lengthened considerably. 20 Nor is there any need to apply burlap as is now the custom, and the time in positioning as well as removing the doors is accordingly considerably shortened. Instead of using 25 one solid built-up door for each door opening, different heights of the door can easily be obtained by using loose boards to build up the door between the jambs and the tightening of the boards is attained in the same manner as already described.

30 As all leakage is now practically eliminated, a great saving for the railway companies using these clamps will be had and such saving is obvious since the largest percentage of claims against the companies is 35 for leaking grain car doors.

The advantage of providing the recesses 29 for the securing bolt heads is that there will be no outside obstruction on the car walls and that the outside sliding doors of 40 the cars can pass in any direction without hindrance.

Having thus described the invention, what is claimed as new is:

45 1. A securing device for doors comprising a pair of posts forming a door opening between them, a door fitting across said opening, an angle bar secured upon the inner side of each post with one flange projecting inwardly from its post, a flap swingingly attached to the inner edge of said inwardly projecting flange and adapted to overlap the edge of the door and bear flat against the inner side of the door, and means on said

post engaging the flap and operable to bind the flap against the door and the door in 55 position extending across the door opening.

2. The combination with the wall of a car having a door opening therein, of a door fitting across said opening, a supporting member on the inner side of the wall of the 60 car, a jamb on the inner side of the wall of the car between the door opening and the supporting member, a flap swingingly attached to the supporting member and adapted to overlap the edge of the door and bear 65 flat against the inner side of the door, and means mounted in the jamb and housed in the wall of the car and engaging the flap to bind the same against the door and the door against the wall of the car. 70

3. The combination with a car wall having a door opening therein, of a door fitting across said opening, a flange projecting inwardly from the inner side of the car wall at the side of the door opening, a flap swingingly attached to said flange and adapted to overlap the edge of the door and bear flat against the inner side thereof, a jamb on the inner side of the car wall between the flange and the door, and a clamping bolt threaded through the jamb and provided with a head at each end, one end of the bolt being housed in the car wall and operable from the outer side thereof and the opposite end of the bolt being loosely engaged in the flap whereby to bind the flap against the door and the door against the car wall. 80 85 90

4. The combination with a car wall having a door opening therein and a recess in its outer side at the side of the door opening, of a door fitting across said opening, a flange projecting inwardly from the inner side of the car wall, a flap swingingly attached to said flange and adapted to overlap the edge of the door and bear against the inner side thereof, a jamb between the flange and the door, and a clamping bolt threaded through the jamb and provided with a head at each end, the inner head engaging said flap to swing the same against the door and the outer head being housed in the recess in the outer side of the car wall. 95 100

In testimony whereof I affix my signature.

JAMES E. COSSAIRT. [L. s.]
